SHOWER BATH STALL

Rebecca D. Steele, 8680 E. Alameda Ave.,
Denver, Colo. 80231

Continuation-in-part of abandoned design application Ser.
No. 375,480, July 2, 1973. This application May 19,
1975, Ser. No. 578,909

Term of patent 14 years

Int. Cl. D23—02

U.S. Cl. D23—57

Fig. 1

Fig. 2

Fig. 5

Fig. 6

Fig. 7

FIG. 1 is a perspective view taken from the front and right side of a shower bath stall showing my new design;

FIG. 2 is a perspective view taken from the rear and left side thereof;

FIG. 3 is a top plan view thereof;

FIG. 4 is a cross-sectional view taken on line 4—4 of FIG. 3;

FIG. 5 is a cross-sectional view taken on line 5—5 of FIG. 3;

FIG. 6 is a cross-sectional view taken on line 6—6 of FIG. 3; and

FIG. 7 is a cross-sectional view taken on line 7—7 of FIG. 3.

This is a continuation-in-part of design application Ser. No. 375,480, filed July 2, 1973, now abandoned.

I claim:

The ornamental design for a shower bath stall, substantially as shown.
